UNITED STATES PATENT OFFICE.

JAMES SAMUEL KING, OF LONDON, ENGLAND, ASSIGNOR OF ONE-HALF TO CHARLES KNIGHT & COMPANY, LIMITED.

LOOSE-LEAF LEDGER AND THE LIKE.

Application filed August 23, 1921. Serial No. 494,502.

To all whom it may concern:

Be it known that I, JAMES SAMUEL KING, a subject of the King of Great Britain, residing at 227-239 Tooley Street, London, 5 England, have invented a new and useful Improvement in Loose-Leaf Ledgers and the like, of which the following is a specification.

The object of this invention is to provide 10 an improved means for securing the loose leaves of ledgers and the like of the type in which two or more straps secured to the inside of the back of the cover pass through the loose leaves and through followers at the 15 end and beginning of the leaves and into the interior of the front of the cover which is made double; within the front of the cover they are secured to a cross bar which is parallel to the hinge and is capable of slight 20 movement towards and away from the hinge.

According to this invention the cross bar has attached to it an actuating strap which passes towards that end of the front which 25 is remote from the hinge and is then bent around a fixed transverse bar and beneath a second bar parallel to that just mentioned towards the hinge.

My invention is illustrated by the accompanying drawings, Figure 1 of which is a perspective view of part of a loose leaf ledger constructed according to the invention, part of the inside of the front cover being cut away to show the mechanism, Figure 2 is a plan of part of such a ledger with the front cover open and Figure 3 is a section on the line 3-3 of Figure 1.

A, A, A, are three straps which are secured to the inside of the back B of the 40 cover; these pass through loose leaves C and through followers D, D, into the interior of the front E of the cover within which they are secured to a cross bar F which is parallel to the hinge G and is capable of movement 45 within the front of the cover. Attached to the cross bar F is an actuating strap H which passes towards the edge of the cover E and is bent around and over a cross bar I and threaded beneath a second 50 cross bar J lying parallel to and just above the bar I and covered with a strip of leather or other suitable material K. The strap H is then bent back upon itself as shown most clearly in Figure 3 and its end is tucked in 55 between the two bars I and J. L is a tongue

or extra length of strap which is secured to the free end of the strap H to enable the latter more readily to be pulled out from between the bars I and J. The free end of the tongue L may be tucked in through a slit so 60 as to give a neat appearance to the whole.

Thus when the front E of the cover has been opened if the back B of the cover is grasped by the right hand and the front by the left hand the front can be pulled away 65 from the back. This results in the straps A where they cross the hinge G and pass through the leaves C being slackened, whereupon any leaf which is threaded in the usual manner on to the straps acting as posts can 70 be detached from the straps and removed from the book. When it is desired to secure the leaves the free end of the strap H or the tongue L can be grasped by the right hand and the outer edge of the front of the cover 75 by the left hand, then by pulling the strap H towards the hinge G the cross bar F is drawn away from the hinge and consequently the front of the cover is drawn into close engagement with the front follower D and 80 thus the leaves are held tightly. In order to secure the book in this last position the free end of the strap H may be bent over itself and tucked in beneath a flap K secured to the bar I, so as to produce a wedging action 85 by which the strap H is securely locked against movement.

What I claim is:—

1. In a loose leaf ledger, the combination of a cover including a front, a back and a hinge for connecting the front and the back, a cross bar movable parallel to the hinge and movable within the front of the cover, straps secured at one end to the inside of the back of the cover and at the other end to the cross 90 bar, a transverse bar secured within the front of the cover between the cross bar and the edge of the cover, an actuating strap having one end fixed to the cross bar and bent around the transverse bar and means for 95 securing this strap.

2. In a loose leaf ledger, the combination of a cover including a front, a back and a hinge for connecting the front and the back, a cross bar movable parallel to the hinge 105 and movable within the front of the cover, straps secured at one end to the inside of the back of the cover and at the other end to the cross bar, a transverse bar secured within the front of the cover and between the cross 110

bar and the edge of the cover, a second transverse bar above the first and also secured within the front of the cover and an actuating strap secured to the cross bar, passed beneath the first transverse bar and then between the two transverse bars.

3. In a loose leaf ledger, the combination of a cover including a front, a back and a hinge for connecting the front and the back, 10 a cross bar movable parallel to the hinge and movable within the front of the cover, straps secured at one end to the inside of the back of the cover and at the other end to the cross bar, a transverse bar secured within the front 15 of the cover and between the cross bar and the edge of the cover, a second transverse bar above the first and also secured within the front of the cover and an actuating strap secured to the cross bar, passed beneath the first transverse bar and then between the two transverse bars.

4. In a loose leaf ledger, the combination of a cover including a front, a back and a hinge for connecting the front and the back 25 a cross bar movable parallel to the hinge and movable within the front of the cover, straps secured at one end to the inside of the back of the cover and at the other end to the cross bar, a transverse bar secured within the front 30 bar, a transverse bar secured within the front

of the cover and between the cross bar and the edge of the cover, a second transverse bar which is secured to the inside of the front of the cover just above the first transverse bar and provided with a leather covering 35 having a tongue protruding towards the hinge of the cover and an actuating strap secured to the cross bar, passed beneath the first transverse bar and then between the two transverse bars.

5. In a loose leaf ledger, the combination of a cover including a front, a back and a hinge for connecting the front and the back, a cross bar movable parallel to the hinge and 40 movable within the front of the cover, straps secured at one end to the inside of the back of the cover and at the other end to the cross bar, a transverse bar secured within the front 45 of the cover and between the cross bar and the edge of the cover, a second transverse bar above the first and also secured within the front of the cover and an actuating strap which is secured to the cross bar and which is passed beneath the first transverse bar 50 and then between the two transverse bars 55 and has a tongue secured to its free end.

In testimony that I claim the foregoing as my invention I have signed my name this 10th day of August, 1921.

JAMES SAMUEL KING.
